UNITED STATES PATENT OFFICE

2,643,123

GRIP TYPE EXERCISING DEVICE

Joseph Milton Spinks, Atlanta, Ga.

Application August 24, 1949, Serial No. 111,985

1 Claim. (Cl. 272-68)

1

The invention relates to an exercising device and has as an object the provision of a simple device for exercising particularly the "grip" and the muscles of the forearm.

It is an object of the invention to provide a device of the character referred to that is adjustable for use by persons with various size hands.

It is a further object of the invention to provide a device such that the amount of work required for its operation is determined directly by the user.

It is a still further object to provide a device for exercising the flexor muscles of the forearm both during their contraction and during their relaxation, the latter by resistance to the contraction of the muscles of the opposite forearm.

Further objects of the invention will appear from the following description when read in connection with accompanying drawings illustrating embodiments of the invention and wherein:

Figure 1 is a side elevation of one form of the invention;

Figure 2 is a vertical section on line 2-2, Figure 1;

Figure 3 is a side elevation of a different form of the invention;

Figure 4 is a vertical section on line 4-4, Figure 3;

Figure 5 is a side elevation of still a further form of the invention;

Figure 6 is a vertical section on line 6-6, Figure 5.

As shown in Figures 1 and 2, the device comprises: a bar 10 having grip or handle portions 11, 12 and a spacer 13 secured to the center of bar 10.

The spacer 13 as shown comprises: a pair of spaced uprights 14 and 15 and a center saddle 16 shown as secured by means of a bolt 17 to the center portion of bar 10. To support a second bar or lever 18 there is shown a pin 19 passing through openings 20 in the uprights 14 and 15 whereby the bar 18 is pivoted for movement as indicated in dotted lines in Figure 1. The grip or handle portions 11, 12 and 20, 21 are shown as U-shaped members pivoted at their centers upon the bars 10 and 18.

In use, the device is grasped with the respective hands grasping the grips 11, 20 and 12, 21 and the bars are moved about the pin 19 by the grip of the hands, the separation of one pair of handles being resistingly resisted by relaxing the grip of that hand as the other hand contracts. The amount of work applied at each contraction of a hand may therefore be adjusted by the amount of resistance applied by the other hand.

2

In the form of the invention shown in Figures 3 and 4 the uprights 14', 15' are shown as covered by U-shaped member 22 secured by a bolt 23 to the said uprights. Also as shown in Figure 3 a grip or handle 24 is revoluble upon the pivoted bar, the grip 24 being prevented from escape at the end of the bar 18' by flaring of the end of the tube constituting the bar as shown at 25 and the grip being prevented from moving toward the center of the bar by means of a screw or rivet 26. In the use of the device with a revoluble grip as shown at 24, the grip or handle may roll in the fingers of the hand, the thumb of which hand grasps the handle 27. When grasped as described, exercising with the device passively rolls the fingers out while the thumb remains in a more or less flexed position on handle 27. It is to be understood that a revoluble grip such as 24 may be placed at each end of the bar 18'.

The form of Figure 5 utilizes the saddle member 16 of Figure 2 in combination with the U-shaped cover 22 of Figure 4.

The device may be made of a variety of materials. The forms illustrated in Figures 1-6 are peculiarly adapted to be produced in metal.

While directly the use of the device of the invention will only develop the muscles of the forearms, the biceps, triceps, and other muscles 30 may also be simultaneously exercised in the same manner as is done with dumb-bells.

I claim:

An exercising device comprising, in combination: a pair of bars; handle means carried by 35 the respective ends of each of said bars, at least one of said handle means revoluble about the axis of its bar; and means providing a spaced pivotal connection intermediate the ends of said bars whereby when the device is grasped with 40 one hand at each end of the bars and the grip by each hand is alternately relaxed and increased the bars are allowed to work back and forth and the revoluble handle rolls in the hand.

JOSEPH MILTON SPINKS.
